UNITED STATES PATENT OFFICE

HARRY E. CROSBY, OF HUNTINGTON PARK, CALIFORNIA, ASSIGNOR TO CALIFORNIA CRUSHED FRUIT CORPORATION, OF LOS ANGELES, CALIFORNIA, A CORPORATION OF DELAWARE

DESIGN FOR A BEVERAGE DISPENSER

Application filed June 20, 1930. Serial No. 36,113. Term of patent 7 years.

To all whom it may concern:

Be it known that I, HARRY E. CROSBY, a citizen of the United States, residing at Huntington Park, in the county of Los Angeles and State of California, have invented a new, original, and ornamental Design for Beverage Dispensers, of which the following is a specification, reference being had to the accompanying drawing, forming part thereof, in which Fig. 1 is a front elevation of a beverage dispenser, showing my new design; and Fig. 2 is a plan view on a reduced scale.

I claim:

The ornamental design for a beverage dispenser, as shown.

HARRY E. CROSBY.
